UNITED STATES PATENT OFFICE.

FRANK C. H. STRASBURGER, OF KNOX, INDIANA.

SPARK-PLUG PUMP.

1,139,917.

Specification of Letters Patent. Patented May 18, 1915.

Application filed February 12, 1915. Serial No. 7,747.

To all whom it may concern:

Be it known that I, FRANK C. H. STRASBURGER, a citizen of the United States, residing at Knox, in the county of Starke and State of Indiana, have invented certain new and useful Improvements in Spark-Plug Pumps, of which the following is a specification.

This invention relates in general to pneumatic pumps and more particularly to a pump which is adapted to replace the spark plug in one cylinder of a multi-cylinder internal combustion engine and to be utilized to supply air to the pneumatic tires of a vehicle.

It is the principal object of my present invention to provide a spark plug pump which may permanently replace the usual spark plug and which may, at will, be utilized either as a spark plug or as a pump, the change being effected by a simple movement.

It is a further object of my invention to provide a spark plug pump which will function as a spark plug or as a pump, as desired, and in which the parts not in use will in no way interfere with the proper functioning of the parts in use.

A still further object of my invention is to provide a spark plug pump comprising a minimum number of simple and relatively inexpensive parts which may be readily assembled to produce the device at a comparatively low cost.

Other objects and advantages of my invention are apparent as it is better understood by reference to the following specification when read in connection with the accompanying drawing in which—

Figure 1 is a vertical section through the device; Fig. 2 is a vertical elevation thereof with the lower portion in section, the direction of view being normal to that of Fig. 1; Fig. 3 is an elevation of the sectioned portion of Fig. 2, and Fig. 4 is an elevation of the sectioned portion of Fig. 2, the direction of view being normal to that of Fig. 3.

Referring to the drawings, 1 indicates the cylinder of an internal combustion engine having the usual threaded opening 2 in which the spark plug (not shown) is normally disposed. A coupling 3 is threaded into the opening 2 and supports the device which forms the subject-matter of my present invention. It is to be understood that spark plugs are made in several standard sizes and different engines have spark plug openings to accommodate spark plugs of a

particular size. By providing an interchangeable coupling 3 I am enabled to adapt my device for use with internal combustion engines having spark plug openings of different sizes.

Threadedly mounted on the coupling 3 is a casing comprising a lower portion 4 which is preferably a malleable casting and an upper portion 5 which is preferably of drawn metal, the two portions being secured together by a coupling ring 6 threadedly mounted on the portion 4 and having a flange 7 to engage the flange 8 of the portion 5. The lower part of the casing 4 is provided with a tapered opening 9 in which the valve plug 10 is rotatably mounted, the plug being held in position by a nut 11 on a threaded extension 12 thereof, which in turn engages a spring 13 bearing against the washer 14, the edges of which bear on the face of the casing about the opening 9. The plug 10 is provided with an extension 15 at its opposite end and a suitable operating handle 16 is mounted thereon, whereby the plug may be turned about its axis, the movement being limited, however, by the engagement of a pin 17 mounted in the plug 10 with the shoulders 18 and 19 on the casing.

The valve plug 10 is of skeleton form, providing with the sides of the opening 9, a chamber 20 within which an electric terminal 21 is suitably mounted and adapted to be disposed in sparking relation with the terminal 22 of a spark plug 23, mounted in an extension 24 of the casing, when the plug 10 is at one extremity of its rotative movement. It is to be understood that the chamber 20 is always in communication with the interior of the engine cylinder 1.

A puppet valve 25 having a head 26 cooperating with an inlet 27 in the wall of the chamber 20 is slidably mounted in the extension 15 of the valve plug 10, the head 26 being normally seated by a spring 28, surrounding the stem 25 between the nut 29 on the end of the stem and an abutment 30 within the extension 15. A duct 31 is provided in the valve plug 15 behind the head 26 of the puppet valve which, when the valve is turned to the position indicated in Figs. 3 and 4 of the drawing, registers with the cut-away portion 32 of the casing to allow air to be drawn past the head 26 of the puppet valve into the chamber 20 and thence into the interior of the engine cylinder 1. When the valve plug 10 is moved to the other extremity of its rotative movement

the duct 31 no longer registers with the cut-away portion 32 and the entrance of air from the exterior of the casing is thereby prevented. This is the position indicated in Figs. 1 and 2 in which the terminals 21 and 22 are disposed in sparking relation. An insulating insert 33 is mounted in the valve plug 10 in position to be disposed opposite the terminal 22 when the valve plug 10 is turned to allow outside air to pass into the chamber 20 through the inlet 27.

A plate 34 is disposed between the end of the lower portion 4 of the casing and the flange 8 of the upper portion 5 thereof and is adapted to divide the casing into two sections, the lower of which forms one of the pump cylinders. A flange 35 on the plate 34 supports a cylinder 36 threaded thereto and having a head 37 threaded to the upper end thereof, forming the second pump cylinder. The head 37 is provided with openings 38 through which air may escape therefrom to an air-collecting and air chamber formed by the portion 5 of the casing, the openings 38 being normally closed by a valve comprising a leather washer 39 and a metal washer 40 which are normally held in close relation with the head 37 by a spring 41, disposed between the washer 40 and a cotter pin 42, which passes through an extension 43 of the head 37.

Between the lower end of the cylinder 36 and the plate 34 a stuffing box comprising a pair of metal washers 44 and a pair of leather washers 45 is disposed and adapted to form an air-tight opening through which the hollow plunger rod 46 may slide. Upon the lower end of the plunger rod 46 a head 47 is threadedly mounted and provided with a packing ring 48 to coöperate with the walls of the cylinder. A member 49 is threaded on the plunger rod 46 below the head 47, a leather washer 50 being disposed therebetween, and is provided with a reduced portion 51, forming a cage for the ball valve 52, and which also serves to prevent knocking as the plunger reciprocates by trapping air between the member 49 and the lower end wall of the cylinder. Openings 53 near the upper extremity of the cylinder allow free ingress and egress of air to and from the cylinder above the head 47 as it reciprocates. The openings 53 are, however, spaced from the plate 34 so that air is trapped between the head 47 and the plate 34 near the end of the upward stroke to prevent knocking. The rod 46 has a duct 54 extending from the lower end nearly to its upper extremity where the openings 55 are provided to allow air to pass into the upper cylinder. The lower end of the rod 45 is notched at 56 to allow air to pass around the ball 52 and upward through the rod 46 into the upper cylinder. A head 56 is threadedly mounted at the upper end of

the rod 46 within the upper cylinder, a leather washer 57 being disposed below the head 56 and held in place by the washer 58, the diameter of the head and washer 58 being slightly less than the diameter of the cylinder so that as the head 56 moves downwardly the air trapped beneath it, which is prevented from returning by the ball valve 52, will be forced around the washers 58 and 57 and the head 56 into the upper cylinder 36 above the head 56 where it will be compressed and driven into the air chamber upon the succeeding upward movement of the plunger. The air chamber is provided with an outlet 59 which may be connected by means of suitable hose (not shown) with the tire to be filled, the gage 60 indicating the pressure in the tire and air chamber.

It is believed that the operation of my device will be apparent without further description of the structure thereof. The device is permanently mounted in the cylinder head of the engine and normally the valve plug 10 is disposed in the position indicated in Figs. 1 and 2 in which position the inlet for outside air and the outlet to the pump cylinders are closed and the terminals 21 and 22 are in sparking relation. In this position gas is regularly drawn into the cylinder from the carburetor and fired by the spark passing between the terminals 21 and 22.

When it is desired to supply air to tires the outlet 59 in the air chamber is connected by means of suitable hose to the tire and the valve plug 10 is turned by means of the operating handle 16 to the position indicated in Figs. 3 and 4, in which position the terminals 21 and 22 are separated, the insulating insert 33 is disposed opposite the terminals 22 and the inlet and outlet of the chamber 20 are open to the outside air and to the pump cylinders respectively. If the engine is then started the remaining cylinders will cause the piston in the cylinder 1 to reciprocate, drawing air through the duct 31 and puppet valve 25 into the chamber 20 and thence into the engine cylinder upon the downward stroke, and forcing this air upwardly through the outlet of the chamber 20 beneath the member 49 and past the ball valve 52 through the duct 54 in the rod 46 and into the upper cylinder 36 beneath the washer 58. The pressure will cause the rod 46 to move upwardly carrying the head 56 in the upper cylinder 36, compressing the air contained therein and forcing it into the air chamber and thence into the tire. Upon the succeeding downward movement of the engine piston the suction will cause the rod 46 to move downwardly while the engine cylinder will be again filled with air entering through the duct 31 and the puppet valve 25. The air in the upper cylinder 36 beneath the washer

58 is prevented from returning by the ball valve 52 which immediately seats when the suction begins and the air will accordingly be forced around the washers 58 and 57 and 5 head 56 into the cylinder 36 above the head 56 ready for the succeeding compression. When the pressure in the tires is satisfactory, as indicated by the gage 60, the valve plug 10 is returned to its normal position 10 by means of the operating handle 16 and the cylinder 1 will immediately resume its normal function.

It will be readily understood that I have devised a simple and efficient spark plug 15 pump which may be permanently attached in position upon the end of the cylinder in place of the usual spark plug and which will perform the usual functions of the spark plug, the pump in no way interfering with 20 the normal operation of the engine but being always ready for instant operation when required with a minimum amount of manipulation.

It will be apparent that various changes 25 may be made in the form, construction and arrangement of the parts without departing from the spirit and scope of the invention or sacrificing any of its material advantages, the form hereinbefore disclosed being merely 30 one preferred embodiment thereof.

I claim:

1. In a device of the character described, the combination of a chamber, having an outlet and an inlet, a movable closure for 35 said outlet, and a pair of electric terminals within said chamber, one of said terminals being movable into sparking relation with the other simultaneously with the closure of said outlet.

40 2. In a device of the character described, the combination of a chamber, having an outlet and an inlet, a movable closure for said inlet, and a pair of electric terminals within said chamber, one of said terminals being movable into sparking relation with 45 the other simultaneously with the closure of said inlet.

3. In a device of the character described, the combination of a chamber having an outlet and an inlet, a movable closure for said outlet and inlet, and a pair of electric terminals within said chamber, one of said terminals being movable into sparking relation with the other simultaneously with the closure of said outlet and inlet.

4. In a device of the character described, the combination of a chamber, having an outlet and an inlet, a movable closure for said outlet, a stationary electric terminal within said chamber, and an electric terminal secured to said movable closure and adapted to be disposed in sparking relation with said stationary terminal when said outlet and inlet are closed.

5. In a device of the character described,

the combination of a chamber, having an outlet and an inlet, a movable closure for said inlet, a stationary electric terminal within said chamber, and an electric terminal secured to said movable closure and adapted to be disposed in sparking relation with said stationary terminal when said inlet is closed.

6. In a device of the character described, the combination of a chamber having an outlet and an inlet, a movable closure for said outlet and inlet, a stationary electric terminal within said chamber, and an electric terminal secured to said movable closure and adapted to be disposed in sparking relation with said stationary terminal when said outlet and inlet are closed.

7. In a device of the character described, the combination of a chamber having an outlet and an inlet, a movable closure for said outlet and inlet, a check valve in said inlet, an electric terminal secured to said movable closure and adapted to be disposed in sparking relation with said first-mentioned terminal when said outlet and inlet are closed.

8. In a device of the character described, the combination of a chamber having an outlet and an inlet, a movable closure for said outlet and inlet, an electric terminal within 95 said chamber, an electric terminal secured to said movable closure, and means for actuating said closure to close said outlet and inlet and simultaneously dispose said terminals in sparking relation.

9. In a device of the character described, the combination of a chamber having an outlet and an inlet, a check valve in said inlet, an electric terminal within said chamber, rotatable means to close said outlet and inlet, 105 and an electric terminal secured to said rotatable means and adapted to be moved into sparking relation with said first-mentioned terminal when said outlet and inlet are closed.

10. In a device of the character described, the combination of a chamber having an outlet and an inlet, an electric terminal within said chamber, rotatable means to close said outlet and inlet, an electric terminal secured 115 to said rotatable means and adapted to be moved into sparking relation with said first-mentioned terminal, when said outlet and inlet are closed, and out of sparking relation therewith when said outlet and inlet are open, and an insulating member carried by said rotatable means and adapted to be disposed contiguous to said first-mentioned terminal when said outlet and inlet are open.

11. In a device of the character described, 125 the combination of a chamber having an outlet and an inlet, a movable closure therefor, a stationary electric terminal within said chamber, an electric terminal secured to said movable closure and adapted to be disposed 130

in sparking relation with said stationary terminal when said outlet and inlet are closed and out of sparking relation therewith when said outlet and inlet are open, and means for 5 securing said chamber in communicative relation with the interior of an engine cylinder.

12. In a device of the character described, the combination of a chamber having an 10 outlet and an inlet, a movable closure for said outlet and inlet, a check valve in said inlet, a stationary electric terminal within said chamber, an electric terminal secured to said movable closure and adapted to be dis- 15 posed out of sparking relation with said stationary terminal when said outlet and inlet are open, air-compressing means connected to said outlet, and means for securing said chamber in communicative relation 20 with the interior of an engine cylinder.

13. In a device of the character described, the combination of a chamber having an outlet and an inlet, a movable closure for said outlet and inlet, a check valve in said 25 inlet, a pair of electric terminals within said chamber, one of said terminals being movable out of sparking relation with the other simultaneously with the movement of said closure to open said outlet and inlet, a pair 30 of cylinders, plungers in said cylinders, means for conveying air from said outlet to said cylinders, means to prevent the return of air from one of said cylinders, an oil-col- 35 lecting and air chamber connected to one of said cylinders, means to prevent the return of air from said air chamber to said cylinder, means for securing said first-mentioned chamber in communicative relation with the interior of an engine cylinder.

40 14. In a device of the character described, the combination of a chamber having an outlet and an inlet, a movable closure for said outlet and inlet, a check valve in said inlet, a pair of electric terminals within said 45 chamber, one of said terminals being movable out of sparking relation with the other simultaneously with the movement of said closure to open said outlet and inlet, a pair 50 of cylinders, plungers in said cylinders, means for conveying air from said outlet to said cylinders, means to prevent the return of air from one of said cylinders, means at either end of one of said cylinders to cushion 55 the plungers therein and means for securing said first-mentioned chamber in communicative relation with the interior of an engine cylinder.

15. In a device of the character described, the combination of a chamber having an outlet and an inlet, a movable closure for said outlet and inlet, a check valve in said inlet, a pair of electric terminals within said

chamber, one of said terminals being movable out of sparking relation with the other simultaneously with the movement of said closure to open said outlet and inlet, a pair of cylinders, plungers in said cylinders, means for conveying air from said outlet to said cylinders, means to prevent the return of air from one of said cylinders, an oil-collecting and air chamber having an outlet connected to one of said cylinders, means to prevent the return of air from said air chamber to said cylinder, and an interchangeable coupling for securing said first-mentioned chamber in communicative relation with the interior of an engine cylinder. 70 75

16. In a device of the character described, the combination of a casing comprising separable sections and coupling means for holding said sections in coöperative relation, a chamber in one of said sections having an outlet and an inlet, a movable closure for said outlet and inlet, a pair of electric terminals within said chamber, one of said terminals being movable out of sparking relation with the other simultaneously with the movement of said closure to open said outlet and inlet, air compressing means within said casing and connected to said outlet, and means for securing said casing to an engine cylinder with said chamber in communicative relation with the interior of said cylinder. 80 85 90

17. In a device of the character described, the combination of a chamber having an outlet and an inlet, a single movable closure for said outlet and inlet, a check valve in said inlet, a pair of electric terminals, a pair 100 of cylinders, plungers in said cylinders, means for conveying air from said outlet to said cylinders, means to prevent the return of air from one of said cylinders, and means for securing said first-mentioned chamber in communicative relation with the interior of an engine cylinder. 95

18. In a device of the character described, the combination of a chamber having an outlet and an inlet, a single movable closure for said outlet and inlet, a check valve in said inlet, a pair of electric terminals, a pair 110 of cylinders, plungers in said cylinders, means for conveying air from said outlet to said cylinders, means to prevent the return of air from one of said cylinders, means at either end of one of said cylinders to cushion the plungers therein, and means for securing said first-mentioned chamber in communicative relation with the interior of an engine cylinder. 115
